PROCESS FOR CRACKING OILS

Allan V. Ritchie, Elizabeth, N. J., assignor to The
Texas Company, New York, N. Y., a corporation
of Delaware

Application February 4, 1930, Serial No. 425,745

6 Claims. (Cl. 196—48)

The present invention relates in general to a process for the conversion of higher boiling hydrocarbon oils into lower boiling oils, and more particularly, to improvements in the manner of handling the charge introduced into a continuously operating system.

It has been the common practice for some time to operate cracking units of various types in such a way as to permit a more or less continuous flow of a charge of oil through heating chambers under pressure, with the result that the conversion of higher boiling oils may take place uninterruptedly for a considerable period.

It has also been a recognized practice to mix with the charge of fresh oil, which is being constantly fed into the system, the condensate from the air condensers or bubble towers, or similar cooling devices through which the vapors resulting from the cracking process are led.

Under the usual methods of this type now being employed, the refluxed or backtrapped condensate is introduced into the charge of fresh oil before the latter enters or as it passes through the main heating unit such as a preheating coil.

In connection with continuous cracking processes of the type mentioned, it has been recognized as highly advantageous to pass only comparatively clean stock, composed of the fresh charge and the refluxed condensate, through the heating elements, such as coils, which are subjected to the greater portion of the applied heat. The reason for this, as is well known, is to reduce as far as possible the excessive formation of carbon deposits on the walls of the tubes or vessels in which the oil is being heated. In spite of all care which may be exercised in the operation of cracking units of various types now employed, it is found necessary to shut down each unit at periodic intervals for the purpose of cleaning out the heavy deposits of sludge and carbon which gradually accumulate in certain parts of the system. This applies to all forms of presently known cracking installations, and while the period of continuous operation may vary with a number of factors, a fair percentage of total available time is required for these shutdowns to clean out and repair the units. The presence of carbon, furthermore, at points where the most intense heat is applied, has given rise frequently to the failure of the tubes or vessels containing the oil undergoing conversion. Failures of this character not only entail expense in the repair of the system and in the loss of oil contained in the system at the time of the failure, but considerable danger

for those in the neighborhood of the unit is involved.

By the improvements contemplated by the present invention, the period of continuous operation of a cracking system may be prolonged to a considerable extent beyond that ordinarily possible with previously known methods. This will enable the use of the equipment during the greater percentage of the available time and will reduce the losses, due to shut-down for cleaning and repair purposes, to a minimum. Furthermore, by virtue of the present improvements, the failure of tubes or vessels carrying the oil undergoing conversion, will be materially reduced if not altogether eliminated. It is an object of the invention in addition to providing the foregoing benefits to so modify the present practice as to bring about a higher percentage in the yield of gasoline from a given quantity of charge entering the system and to improve generally the efficiency of cracking units.

Toward the end of bringing about the above mentioned advantages, the present invention contemplates the passage of only refluxed condensate through those portions of the tubing or vessels, carrying the oil undergoing conversion, which are subjected to the most intense heat. At least three important advantages among those already specified are derived from this method of handling the charge entering the system. In the first place the excessive formation of carbon on the hottest surfaces of the system is largely eliminated because little or no free carbon is carried in suspension in the refluxed condensate. In the second place this condensate which represents the most difficultly convertible portion of the total charge handled by the system is passed through the hottest portion of the system and is therefore given the greatest opportunity for breaking up into lower boiling oils. A third advantage is that overcracking of certain constituents of the original charge, which frequently takes place under the common practice, is prevented by diverting the more easily cracked components of the fresh charge from the hottest portions of the system.

Another feature of the invention is in the manner of returning the reheated refluxed condensate to the main body of oil in the system. It is proposed in this connection to produce greater uniformity in the condition of the charge throughout its course in the system by introducing the refluxed material, after it has been independently reheated, at a point in the system where the heavier oils are collected. As is well known in any cracking system, the process of conversion tends to produce a residual body of

oil which, as it passes through the system, becomes constantly heavier and more viscous. This is due largely to the fact that the lighter or lower boiling constituents are constantly being carried away. Therefore, the introduction of the relatively light reheated, refluxed condensate into the system at a point where the later stages of the conversion process are going on tends to balance off the natural increase in density encountered at this point. Furthermore, as a result of this introduction of the refluxed constituents, at a later stage in the process than heretofore, the load upon the hot oil or surge pumps which handle this refluxed material is reduced to a considerable extent. This is due to the fact that the pressure at the point of introduction is lower and the surge pumps will not have to overcome the pressure built up by the fresh charge pumps so that as a consequence the operating expense is appreciably reduced.

With the foregoing and other incidental objects in view, the invention will now be described in connection with the accompanying drawing in which Fig. 1 is a diagrammatic showing of certain apparatus and connections for carrying out the invention, and Fig. 2 diagrammatically illustrates a modification of a part of the system shown in Fig. 1.

For the purpose of illustrating the invention, it has been disclosed with relation to a cracking unit of the type employing a preheating coil through which the charge of oil is first passed before being passed into one or more vertical drums in which a cracking temperature and pressure is maintained. Thus there may be provided a furnace 1 carrying a plurality of tubes connected in series by suitable manifolds at the ends, thereby creating a long continuous coil such as indicated by the numeral 2 in the drawing. A fresh charge of oil may be introduced into this coil by means of a pump 3a through an inlet pipe 3, and after passing through the series of tubes, may emerge and be conducted by means of a pipe 4 to one or more of the vertical drums or stills, such as designated 5 and 6. Preferably there will be a battery of these vertical stills, four being shown in the drawing, including two additional stills 7 and 8, and all being connected in series by means of pipes 9 just below the liquid level in the drums and by means of vapor lines 10 above the liquid level. The battery of stills may either be merely heat insulated or may be supplied with heat from a suitable source to make up for the heat losses. Vapors of lower boiling oils which result from the conversion process are conducted by means of a pipe 11 to a dephlegmator or condenser or a fractionating column, such as a bubble tower, or similar equipment, such as designated by the numeral 12. The necessary cooling of the tower to provide the proper temperature control may be effected in any suitable way, as by passing the vapors from the top of the tower to a reflux condenser 120 where a portion will be condensed and may be returned as a refluxing medium to the tower. That portion of the vapors which remains in the vapor state may then be led in any suitable way to final condensing apparatus 121 and an accumulator drum 122 for collection while the higher boiling portions which condense or are separated out in the apparatus 12 will be backtrapped by means of pipe 13 to a hot oil surge pump 14. A pipe 15 leading from the output side of the pump may serve to introduce the refluxed condensate into a series of tubes shown diagrammatically in the

form of a coil 16 below the coil 2 in the furnace 1. The other end of coil 16 is preferably connected by a pipe line 17 to one or both of the vertical stills 7 and 8. Suitable valves as shown will preferably be located in the lines 4 and 17 for controlling the distribution of the fresh charge as well as the refluxed condensate. The valve designated 171 may be of ordinary construction or of the pressure reducing type if desired. If of the latter type a higher pressure may be maintained in the coil 16 than is employed in the rest of the system.

Heat is applied in the usual way to the furnace 1 below the coil 16 and it will be apparent that this coil, or the tubes which in effect go to make it up, are subjected to the most intense heat while slightly lower temperatures will prevail in the area surrounding the coil 2. It will be apparent, therefore, that the fresh charge which is somewhat easier to crack than the lower boiling refluxed material, will be subjected to less intense heat than the reflux so that substantially the same rate of conversion may be maintained for both. This will be particularly true if a reducing valve is employed in the line 17 so that higher pressures may be maintained in coil 16. Furthermore it will be noted that the lighter refluxed material is mixed with the heavier residual oil which will have collected in the drums 7 and 8, and will therefore tend to make the contents of all of the drums more uniform in their composition. This, among other things, will tend to prolong the operating period for a single run by virtue of the fact that the carbon deposits will be more evenly distributed. In addition, as hereinabove pointed out, the introduction of the condensate into the later stages of the process, as in the stills 7 and 8, places a less burden upon the surge pump 14 due to the pressure drop occasioned by the frictional resistance to the flow through the coil 2 and the stills 5 and 6. Little or no carbon will be formed in the coil 16 so that the tube failures now commonly encountered will be eliminated or materially reduced.

In order to provide for an emergency, such as created by the failure of a tube, a by-pass in the form of pipe 18 may be provided between the line 15 and the charge line 3. Suitable valves 19 and 20 may then be placed as indicated in the line 15 and pipe 18 respectively. Normally, the valve 19 will be open and the valve 20 will be closed, so that the refluxed material will follow the course above indicated, but in the event of a failure in one of the tubes forming the coil 16, the valve 19 may be closed and the valve 20 opened, so that the reflux will be mixed with the fresh charge and pass through the coil 2. The loss of a considerable quantity of oil will be eliminated in this way and a great deal of the danger connected with a tube failure will be avoided. It will be understood that the drums 5, 6, 7 and 8 are provided with the usual means for drawing off the residual oils from time to time as well as for cleaning out the carbon at the end of a long run.

In cracking systems heretofore employed it has frequently been the practice to construct the preheating coils out of tubes having a diameter of about 3 inches and in instances where certain of the tubes have been arranged to form a section of coil separate from other tubes forming another section of coil the entire charging stock has been merged and passed through at least a

portion of the tubing. According to the present invention, however, the stock is split, as between fresh charge and refluxed material, and passed in parallel relation through separate sections of the preheater. In adapting the present invention to a preheater of an existing cracking unit, therefore, it may be found advisable to change the tubes forming the coils 2 and 16 by reducing them in diameter to say 2½ inches. This will have the effect of maintaining substantially the same speed of flow of the charge as before, and will tend to increase the efficiency of the unit by raising the ratio of heating surface to cross sectional area.

15 As a modification (shown in Fig. 2) of the method of operation already described in the earlier sections the condensate collected in the line 13 from the dephlegmator 12 may be sent directly to the stills 1 and 8, if desired, without being passed first through the preheating coil 16. For this purpose a perforated coil 151 may, for example, be placed in the bottom portions of each of the stills mentioned and the refluxed condensate may be forced through these coils by the pump 14 directly into the heavier oils to be found at these points in the system. The incoming lighter oil will, among other things, as in the previously described method, lessen coke formation 20 in these stills by the tendency to wash out some of the coke in the form of an emulsion along with the tar that is withdrawn from time to time.

While one admirable form of the invention has been described in the foregoing sections, and some 25 variations have been suggested, it will be understood that the present disclosure is illustrative only and that many modifications are contemplated within the scope of the claims which follow.

40 What I claim is:

1. The method of converting hydrocarbon oils into lower boiling products which comprises flowing a confined stream of fresh oil charging stock through a heating coil in a furnace and heating it to cracking temperature during its flow therethrough, discharging the stream of highly heated oil into the first of a plurality of series connected enlarged closed cracking zones through which the oil flows in progression and in which it is maintained at cracking temperature under superatmospheric pressure, withdrawing vapors generated in said enlarged cracking zones and passing them to a fractionating zone wherein undesired higher boiling constituents of said vapors are condensed and thereby separated as reflux condensate, withdrawing and collecting the fractionated vapors, passing reflux condensate in a confined stream directly through a second heating coil in said furnace and heating it during its flow therethrough to a cracking temperature while maintaining it under superatmospheric pressure, burning fuel in said furnace adjacent to said second coil and remote from said first coil whereby the desired degree of heat is imparted to each of said streams, and discharging said independent stream of highly heated condensate into one of said enlarged cracking zones which is subsequent to the said cracking zone into which is discharged the said stream of fresh oil charging stock.

2. The method of converting hydrocarbon oils into lower boiling products which comprises flowing a confined stream of fresh oil charging stock through a heating coil in a furnace and heating it to cracking temperature during its flow there-

through, discharging the stream of highly heated oil into the first of a plurality of series connected enlarged closed cracking zones through which the oil flows in progression and in which it is maintained at cracking temperature under superatmospheric pressure, maintaining substantially uniform pressure conditions in said cracking zones, withdrawing vapors generated in said enlarged cracking zones and passing them to a fractionating zone wherein undesired higher boiling constituents of said vapors are condensed and thereby separated as reflux condensate, withdrawing and collecting the fractionated vapors, passing reflux condensate in a confined stream directly through a second heating coil in said furnace and heating it during its flow therethrough to a higher cracking temperature while maintaining it under superatmospheric pressure, burning fuel in said furnace adjacent to said second coil and remote from said first coil whereby the desired degree of heat is imparted to each of said streams, and discharging the said independent stream of highly heated condensate into one of said enlarged cracking zones which is subsequent to the said cracking zone into which is discharged the said stream of fresh oil charging stock.

3. The method of converting hydrocarbon oils into lower boiling products which comprises flowing a confined stream of fresh oil charging stock through a heating coil in a furnace and heating it to cracking temperature during its flow therethrough, discharging the stream of highly heated oil into the first of a plurality of series connected enlarged closed cracking zones through which the oil flows in progression and in which it is maintained at cracking temperature under superatmospheric pressure, withdrawing vapors generated in said enlarged cracking zones and passing them to a fractionating zone wherein undesired higher boiling constituents of said vapors are condensed and thereby separated as reflux condensate, withdrawing and collecting the fractionated vapors, passing reflux condensate in a confined stream directly through a second heating coil in said furnace and heating it during its flow therethrough to a cracking temperature while maintaining it under superatmospheric pressure, burning fuel in said furnace adjacent to said second coil and remote from said first coil whereby the desired degree of heat is imparted to each of said streams, discharging the said independent stream of highly heated condensate into one of said enlarged cracking zones which is subsequent to the said cracking zone into which is discharged the said stream of fresh oil charging stock and separately withdrawing heavy liquid residual products from said enlarged cracking zones and discharging them from the system.

4. The method of converting higher boiling oils into lower boiling oils which comprises heating a confined flowing stream of fresh oil charging stock to cracking temperature under superatmospheric pressure by passing it through a first heating coil in a furnace, introducing the stream of highly heated oil into an enlarged reaction zone wherein further cracking of the highly heated oil occurs, passing resulting cracked products from said reaction zone into a separate enlarged zone, wherein vapors separate from residue, removing vapors from said zone last mentioned and subjecting them to fractional condensation to separate vapors of desired boiling range from heavier fractions as condensate, heating condensate so formed to a cracking temperature under super-

- atmospheric pressure by passing it through a second heating coil in said furnace, burning fuel in said furnace adjacent said second coil but remote from said first coil whereby the oil in said second 5 coil is heated to a higher temperature than the oil in said first coil, introducing resulting highly heated condensate into said enlarged zone second mentioned at a point remote from that at which vapors are removed therefrom, and condensing the fractionated vapors to form a desired distillate.
- 10 5. The method of converting higher boiling oils into lower boiling oils which comprises heating fresh oil charging stock to cracking temperature under superatmospheric pressure by passing it through a first heating coil in a furnace, introducing the stream of highly heated oil into an enlarged reaction zone wherein further cracking of the highly heated oil occurs, passing the resulting cracked vapors and liquids from said reaction zone into a separate enlarged zone, wherein vapors separate from residue, removing vapors from a point near the top of said zone last mentioned and subjecting them to fractional condensation to separate vapors of desired boiling range from heavier fractions as condensate, heating condensate so formed to a cracking temperature under super- 15 atmospheric pressure by passing it through a second heating coil in said furnace, burning fuel in said furnace adjacent said second coil but remote from said first coil whereby the oil in said second coil is heated to a higher temperature than the oil in said first coil, introducing resulting highly heated condensate into said enlarged zone second mentioned at a point remote from that at which vapors are removed therefrom, and condensing the fractionated vapors to form a desired distillate.
- 20 25 30

ture than the oil in said first coil, introducing the highly heated condensate into said enlarged zone second mentioned at a point near the base thereof, and condensing the fractionated vapors to form a desired distillate.

6. The method of converting higher boiling oils into lower boiling oils which comprises heating fresh oil charging stock to cracking temperature under superatmospheric pressure by passing it through a first heating coil in a furnace, introducing the stream of highly heated oil into an enlarged zone wherein a cracking temperature is maintained and vapors separate from liquids, passing separated liquids from said reaction zone into a separate enlarged zone, wherein vapors 15 separate from residue, subjecting resulting cracked vapors to fractional condensation to separate vapors of desired boiling range from heavier fractions as condensate, heating condensate so formed to a cracking temperature under super- 20 atmospheric pressure by passing it through a second heating coil in said furnace, burning fuel in said furnace adjacent said second coil but remote from said first coil whereby the oil in said second coil is heated to a higher temperature than the oil in said first coil, introducing resulting highly heated condensate into said enlarged zone second mentioned at a point remote from that at which vapors are removed therefrom, and condensing the fractionated vapors to form a desired distillate.

ALLAN V. RITCHIE.
